UNITED STATES PATENT OFFICE

CHARLES A. UFFORD, OF BOSTON, MASSACHUSETTS.

ADJUSTABLE FIGURE-FORM.

SPECIFICATION forming part of Letters Patent No. 248,368, dated October 18, 1881.

Application filed March 7, 1881. (No model.)

To all whom it may concern:

Be it known that I, CHARLES A. UFFORD, a citizen of the United States, residing at Boston, in the county of Suffolk and State of Massachusetts, have invented certain new and useful Improvements in Adjustable Figure-Forms; and I do hereby declare that the same are fully described in the following specification and illustrated in the accompanying drawings.

10 This invention relates to improvements in adjustable figure-forms for displaying or fitting garments on, for which purpose it is carried out as follows, reference being had to the accompanying drawings, in which—

15 Figure 1 represents a front elevation. Fig. 2 represents a central longitudinal section. Fig. 3 represents a cross-section at the waist on the line A B, shown in Fig. 1. Fig. 4 represents a cross-section of the skirt on the line 20 C D, shown in Fig. 1; and Fig. 5 represents the lower part of the bust on the line E F, also shown in Fig. 1.

Similar letters refer to similar parts wherever they occur on the different parts of the drawings.

25 *a* is the base, from which projects upward the center post, *b*, that is screw-threaded in its extreme upper end, and there provided with a nut or screw-threaded handle, *c*, by means of 30 which the various parts of the figure-form are secured together after being adjusted to the desired shape.

35 *d* is a stationary support or bearing on the lower part of the center post, *b*, serving to support the skirt as well as the bust. The skirt is shown as being composed of four laterally-adjustable parts, *e e e e*. It may, however, be made divided in any number of parts, more or less than is shown in the drawings, as 40 may be desired. Near the lower end of the skirt its laterally-adjustable parts *e e e e* are provided with slotted radial arms *e' e' e' e'*, through which the center post *b*, passes loosely. Said radial arms *e' e' e' e'* lie one above and 45 upon the other in the series, and the lowest one rests on the stationary support or bearing *d*, as shown in Figs. 1 and 2. The upper ends of the laterally-adjustable skirt parts *e e e e* are also provided with a series of slotted radial

arms, *e'' e'' e'' e''*, as shown in Fig. 3, through 50 which the center post, *b*, also passes loosely.

f is a hollow pipe surrounding the post, *b* and located thereon between the uppermost of the slotted radial arms *e' e'* and the lowest of the slotted radial arms *e'' e''*, as shown in Figs. 1 55 and 2, and said pipe is provided in its lower end with a suitable flange, nut, or collar, *f'*, and in its upper end with a flange or support, *f''*, which is preferably provided with lips *f''' f'''*, (shown in Figs. 2 and 3,) that serve as 60 guides for the adjustable radial arms *e'' e''*.

If it is desired to lengthen the waist more or less, I introduce between the top of the skirt and the lower end of the bust a waist-block, *g*, preferably made of wood and of a proper 65 thickness, according to the desired adjustment, as shown in Figs. 1 and 2, said waist-block *g* being provided with a slotted opening, *g'*, (shown in Fig. 1,) to allow of its location around the center post, *b*, or it may to equal advantage be made for this purpose in two parts, if 70 so desired.

The bust is made in six parts—viz., laterally-adjustable front *h* and laterally-adjustable back *i*, the laterally-adjustable sides *k k*, and the vertically and laterally-adjustable shoulders *l l*; but this exact number is not material, as I may make the bust in more or less parts, as may be desired. The back and front pieces, *i* and *h*, have in their lower ends, respectively, slotted arms *i'* and *h'*, as shown in Fig. 5, in a similar manner and for a similar purpose as described in relation to the adjustable skirt parts *e e e e* and their slotted arms *e'* and *e''*. In their upper ends the back and front pieces, *i* and *h*, are 85 also provided, respectively, with similar slotted arms, *i''* and *h''*. (Shown in section in Fig. 2.) The sides *k k* are also provided with lower slotted arms, *k'* *k'*, (shown in Figs. 2 and 5,) and upper slotted arms, *k'' k''*, (shown in Fig. 90 2,) in a similar manner and for a similar purpose as heretofore described in relation to the adjustable skirt parts *e e*. The shoulders *l l* are provided in their upper ends with similar radial slotted arms, *l' l'*, (shown in Figs. 1 and 95 2,) through which the center-post *b* passes, as well as through the slotted arms *e', e'', i', i'', h', h'', k', and k''*, in a similar manner and for a

similar purpose, and by means of these arms the various parts of which the bust and skirt are composed can be laterally adjusted to and from the center-post *b*, according to the desired 5 shape and size of the figure form.

m is a pipe surrounding the center post, *b*, between back and front arms, *i' h'*, and side arms, *k' k'*. *n* is a similar pipe on the post *b* between the side arms, *k' k'*, and upper side arms, *k'' k''*. *o* is a similar pipe between the upper side arms, *k'' k''*, and shoulder-arms *l' l'*, and *p* is a pipe or perforated washer between the shoulder-arms *l' l'* and upper back and front arms, *i'' h''*, as shown in Fig. 2, in a similar manner as the 15 pipe on the skirt *e e*. *q* is an ornamented perforated neck-piece, located on the upper end of the post *b* between the arms *h'' i''* and the nut or screw handle *c*, as shown in Figs. 1 and 2. It will thus be seen that all the various laterally-adjustable parts of both the skirt and the 20 bust can be secured in their respective places by tightening the upper nut or screw handle, *c*, by its action on the various slotted radial arms and intermediate pipes heretofore described.

25 For the purpose of raising or lowering the shoulders *ll*, I provide them with slotted plates *rrr*, passing downward beyond the upper edges of the side pieces, *kk*, to which they may be secured in place after being adjusted by means 30 of the set-screws or screws and nuts *r' r' r'*, as shown in Figs. 1 and 2.

The various parts of the bust—viz., *h i k k*,

and *ll*—are made of woven-wire netting, which, after being bent or molded to the required shape, are acidized and dipped in molten tin or solder 35 or alloy, by which a very light, portable, and indestructible bust-form is produced.

What I wish to secure by Letters Patent, and claim, is—

1. In a bust-form, the combination of the laterally-adjustable side pieces, *kk*, with the vertically and laterally adjustable shoulders *ll*, as and for the purpose described. 40

2. In a figure-form, the adjustable waist-block *g* or its equivalent, interposed between the bust 45 and the skirt, as and for the purpose set forth and described.

3. In a figure-form, the center post, *b*, with its stationary support or bearing *d* and nut or screw handle *c*, in combination with the laterally-adjustable skirt-sections *ee* and their radial slotted arms *e' e''* and hollow pipe *f*, the laterally-adjustable bust parts *h i k k l l*, with their radial slotted arms *h' h'' i' i'' k' k'' l'*, and hollow pipes *m n o p*, by means of which the 50 55 adjustable parts of the figure-form can be secured by manipulation of the said nut *c*, in a manner as specified.

In testimony whereof I have affixed my signature in presence of two witnesses.

CHARLES A. UFFORD.

Witnesses:

ALBAN ANDRÉN,
HENRY CHADBOURN.
